[57] **CLAIM**

The ornamental design for a control unit housing for an electrical protection system, as shown and described.

DESCRIPTION

FIG. 1 is a front elevation view of a control unit housing for an electrical protection system embodying our new design;

FIG. 2 is a top plan view thereof;
FIG. 3 is a right side elevation view thereof;
FIG. 4 is a rear elevation view thereof;
FIG. 5 is a left side elevation view thereof;
FIG. 6 is a bottom plan view thereof; and
FIG. 7 is a front perspective view thereof.

FIG. 3
